[57] CLAIM

The ornamental design for a lamp shade, as shown and
described.

DESCRIPTION

FIG. 1 is a top view of a lamp shade showing my new
design;

FIG. 2 is a side elevational view thereof, a view from
the opposite side being identical;

FIG. 3 is a bottom view thereof; and

FIG. 4 is a vertical cross sectional view taken substan-
tially along the line 4—4 of FIG. 1.
